UNITED STATES PATENT OFFICE.

ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

INCLOSED-FUSE TERMINAL.

No. 895,432.

Specification of Letters Patent.

Patented Aug. 11, 1908.

Application filed February 16, 1907. Serial No. 357,647.

To all whom it may concern:

Be it known that I, ROBERT C. COLE, a citizen of the United States, residing in the city of Hartford, Hartford county, Connecticut, have invented certain new and useful Improvements in Inclosed-Fuse Terminals, of which the following is a full, clear, and concise specification.

My invention relates to inclosed fuses for electrical protective purposes, and more particularly to an improved construction for the terminals of such fuses whereby the end closure of the tubular fuse casing and its exterior contact blade are securely joined together, forming a rigid structure adapted to be assembled as a unit with the other parts and capable of being readily put in proper electrical contact with the terminal of the inclosed fuse-link.

To this end the invention involves the combination and arrangement of parts as herein-after described and finally pointed out in the appended claims.

In the drawings, Figure 1 is a longitudinal central section of an inclosed fuse having terminals constructed in accordance with my invention, and showing the fuse-link and its terminals in elevation; Fig. 2 is a plan view thereof; Fig. 3 is a longitudinal section of a modified terminal construction; and Fig. 4 is a further modification.

The fuse illustrated comprises a fuse-link 1 of fusible metal or alloy contained within a casing 2 of fiber or equivalent material and intended to be surrounded by a filling of refractory comminuted material not shown. The fuse-link is electrically connected at each end with the fuse-link terminals 3, which latter may be either integral with the link or attached to it in the manner shown, and said link terminals are respectively connected with the main terminals of the device so that current may pass through the link from one exterior contact blade to the other. The terminals of the device, which may be the same at both ends, each comprise a perforated end closure for the casing 2 in the form of a ferrule 4 and an exterior contact member in the form of a blade 5, which is laid against the end wall of the ferrule and has a hooked or forked end bent over at right angles for purposes of attachment to the line terminals of the circuit in which the device is adapted for use. As thus related the blade and ferrule are united by a tubular means formed

on or attached to one of the aforementioned parts and permanently secured within an aperture in the other.

In the form of the invention shown in Fig. 4 the ferrule and contact member are both provided with aligned apertures, and the securing means consists of a tubular rivet 6 upset within said apertures. The hole through the rivet is occupied by the terminal of the fuse-link, which may be held in place by a drop of solder or by other means adapted to provide a good electrical connection. In the forms of Figs. 1 and 2 the parts of the terminal are similarly arranged, but the tubular securing means is formed as an integral projection or tubular boss 7 on one of the parts and upset inside or against the margin of the aperture in the other part. The hole through the tubular boss is occupied by the link terminal 3 the same as explained with reference to Fig. 4. In both cases the link terminals are concentric with the tubular securing means and with the aperture or apertures in which said means is secured, and in order to strengthen the union between the said parts a stop connection is provided between them in the form of a lug or protuberance on one of said parts engaging with a complementary recess or socket in the other part, such as indicated at 8 (Figs. 1 and 4), so that the blade cannot be accidentally turned upon the ferrule to the detriment of the electrical and mechanical connection. It will be manifest, however, as to this point, that other forms of stop connections may be employed with equal effect.

I have shown in Fig. 3 a further modification of the invention illustrating a reversal of the arrangement of tubular securing means as shown in Figs. 1 and 2. In this form the tubular boss, indicated by 9, is formed as an integral part of the ferrule, being conveniently formed thereon at the same time it is stamped from the blank, and this boss is secured within the aligned aperture in the contact blade 5 by spinning or upsetting, the link terminal being secured within the bore of the boss in the same manner as above described. A stop connection 8 is also shown in this modification.

The above forms of the invention illustrate its use with single fuse-link fuses, but it will be understood that any desired number of fuse-links can be connected with the

end closures of the fuse casing in like manner, and in the case of several such connections the stop lug will obviously be not required.

5. Having described my invention, what I claim and desire to secure by United States Letters Patent, is:

1. As an article of manufacture, an inclosed cartridge fuse consisting of a tubular casing containing a fuse-link with link terminals, an end closure for said casing and a contact member permanently secured to said end closure and forming a structural part of the cartridge fuse, said closure and member being provided with registering apertures receiving the link terminal and the securing means for said closure and contact member comprising a tubular member concentric to said apertures and embracing and secured to the link terminal therein.
2. As an article of manufacture, an inclosed cartridge fuse consisting of a casing containing the fuse-link, an end closure for the casing and a contact member permanently secured to said closure, in combination with tubular securing means for said closure and member, a fuse-link terminal secured within said means and a positive

stop connection between said closure and member adapted to lock the same together. 30

3. An inclosed fuse having a casing and a terminal comprising a ferrule and a contact member, one of said last mentioned parts being provided with an aperture, in combination with a tubular projection formed as 35 an integral portion of the other part and adapted to be secured in said aperture to bind said parts together, and a fuse-link having its terminal secured in said projection.

4. An inclosed fuse having a casing, a fuse-link therein and a terminal for the device comprising an apertured ferrule, and a contact blade having formed thereon a tubular boss located within said aperture and upset 45 against said ferrule, in combination with a fuse-link having its terminal secured within said tubular boss.

In testimony whereof, I have signed my name to the specification in the presence of 50 two subscribing witnesses.

ROBERT C. COLE.
